WEIGHING FEEDER

Elmer E. Harper, Kansas City, Mo.

Application May 27, 1935, Serial No. 23,720

6 Claims. (Cl. 221—118)

The present invention relates to material-feeding apparatus, and particularly to apparatus of this character which operates to continuously feed the material at a uniform rate measured by weight rather than by volume.

The primary purpose of the present invention is to provide a construction of the weighing feeder type, whereby the apparatus may be effectively operated for feeding and delivering material at either a uniform rate, or at a controlled variable rate, as may be required by varying conditions of operation.

For accomplishing this purpose I have devised an improved apparatus in which the feeding mechanism operates in conjunction with a control mechanism through which the feeding mechanism is actuated for both effectively controlling the operation of the feeding mechanism and also regulating the rate of its operation as required 20 by the demands or conditions under which the apparatus is to be operated.

As one method of practicing the invention I employ a feeding mechanism operating in conjunction with scales mechanism, and wherein the control of the feeding mechanism is effected through the medium of a control element responsive to the action of the scales mechanism for producing such variation of the feeding operation as is required for maintaining the scales in proper balance. This control function is accomplished in a positive manner and serves to produce a constant, effective as well as gradual control of the feeding operation, and without in any way interfering with the proper sensitivity and accuracy of the scales function, and the carrying out of the control function serves also to insure, continuously, a substantial uniformity in the discharge of the material by the operation of the feeding means at whatever rate is required. With the foregoing general objects in view, as well as various minor objects which will appear in the course of the detailed specification, the invention will now be described by reference to the accompanying drawing showing apparatus designed for practical operation in accordance with the principles of my improvements, after which the novel and patentable features of the invention will be particularly set forth and claimed.

50 In the drawing—

Figure 1 is a central vertical sectional elevation, showing a material feeding apparatus constructed in accordance with the present invention; and

55 Figure 2 is a plan view of the same.

Referring to the details of construction shown in said drawing, a suitable cabinet or framework 5 is provided in which is mounted a small storage hopper 6 adapted to be placed in receiving relation to a larger storage hopper 7 of any appro-

priate capacity for containing the material to be handled. The exterior of the hopper 6 is provided with lugs 8 for the pivotal attachment of hanger-links 10 which are pivotally connected at their lower ends (as indicated at 11) to the 5 sides of a feeding tray 12, which is thus supported for horizontal shaking or vibratory movement directly beneath the mouth of the hopper 6. The extension 14 forming the lower end or mouth portion of the hopper 6 may be fitted with an 10 adjustable ring 15, which may be manually adjusted to obtain the proper space relationship between the hopper outlet and said tray 12, and secured in its adjusted position by means of set 15 screws 16.

The material which is discharged from the tray 12 (when dislodged therefrom by the reciprocating movement—hereinafter referred to) is directed on to a belt conveyor by means of a pair of troughs or chutes 17, 18, which are shown 20 as suspended by hanger-strips 19 beneath the tray 12, these chutes being of any appropriate relative size, and properly inclined to deliver the material upon the rear or receiving end of said conveyor.

25 This conveyor structure comprises an endless conveyor belt 20 operating around rollers 22 in a framework 24 which carries a platform 25 underlying the top run or span of the belt. The conveyor is maintained in horizontal position by 30 a frame member 27 having its lower end pivoted to an anchoring link 28 which is in turn pivotally anchored at 30 to a fixed portion 31 of the main framework of the apparatus. This arrangement is adapted for supporting the conveyor structure 35 and frame member 27 upon one end of a suitable scale beam 32 in counterbalancing relation to a set of appropriate weights 33 suspended from the other end of said beam.

35 The conveyor belt is driven by means of a gear 40 secured to one of the belt roller shafts 34 and in turn meshing with a drive pinion 36 forming part of a speed changer unit 37, the latter being connected by a flexible shaft 38 with another speed changer unit 39 which is provided with a 45 belt pulley 40. The belt pulley 40 is driven by a belt 41 from a pulley 42 on a countershaft 43 which is mounted in a framework 44 at approximately the same level as the feed tray 12. This shaft 43 is also provided with a cam element 45 and a 50 pulley 46, and this pulley is driven by means of a belt 48 from a suitable motor 50, the speed of which may, if desired, be controlled by means of a suitable rheostat 52.

The cam 45 on the shaft 43 is designed to operate an eccentric member 54 adapted to engage a plate 55 pivoted at its upper end (as indicated at 56) to the framework, and formed at its lower end with a terminal portion 57 in proximity to a terminal 58 at the end of a plate 60 attached to 55

the feed tray 12. A rod 62 is attached to the plate 55 and so actuated by a coil spring 63 as to keep the terminal portion 57 engaged with the eccentric member 54 and thus maintain a 5 gap, or spaced relationship, between the terminals 57 and 58, as shown. The front of the feed tray 12 is also provided with a plate 65 attached to a rod 66 carrying a coil spring 67 acting as a buffer spring in connection with the reciprocating action imparted to the tray in the feeding 10 operation, which will now be described.

When the motor is started it provides a drive through the described pulley and belt connections and flexible shaft 38 for producing a continuous 15 and uniform travel of the conveyor belt 20; it also drives the shaft 43 for operating the eccentric member 54 which constitutes the actuating means for producing the feeding movement of the tray 12. The throw of the eccentric member 54 does 20 not exceed that of the normal gap between the terminals 57 and 58, and the drive across this gap is completed by means of a control element, in accordance with the principle of the control mechanism set forth in my copending application 25 Ser. No. 20,599 filed May 9, 1935.

This control element 10 may be of wedge shape 30 as illustrated, and is supported by an upright bar or rod 12 or the like carried by the framework 24 of the conveyor structure, whereby the element 10 is positioned in the gap between the terminals 57 and 58,—the position of the element 10 being such as to transmit no movement to the tray 12 so long as the scale beam is in exact balance; however, when said frame work 24 rises 35 (due to insufficient load on the conveyor), the said control element 10 also rises, thereby completing the operative connection across said gap between the terminals 57—58 and imparting to the tray a reciprocating movement the extent of 40 which depends upon the extent to which said element 10 is projected into said gap. The balance of the scale mechanism is designed to be maintained by a predetermined amount of the material carried by the belt conveyor during the feeding 45 operation.

After material has been put in the hopper and the motor has been started, since the belt conveyor is, at the beginning, substantially empty it will be overbalanced by the excess weight 33. 50 Consequently that end of the scale beam carrying the control element 10 will rise, presenting said element in position for transmitting reciprocating movement to the tray 12 and resulting in feeding of the material from the hopper and discharging of such material on to the conveyor. 55 This operation will continue until a predetermined weight of material has been deposited upon the conveyor, sufficient to balance the scale beam; this causes the feeding action to stop by withdrawal of the control element 10 from operative 60 or driving position. Again, as soon as discharge of material takes place, by delivery of the material from the front or discharge end of the conveyor, this diminishes the load on the conveyor, causing it to rise and again raising the control element and thus causing the feeding operation to be resumed until the scale balance is restored. 65 In fact there will be more or less of a vertical surging, or "hunting", action of the conveyor at the outset, due to the material not being uniformly distributed on the belt; but this surging gradually dies down as the belt becomes uniformly loaded, after which the control element 70 will operate to feed from the hopper just the right quantity of material necessary for the pur-

pose of maintaining the scale beam in proper balance.

After the operation has been thus started, the rate of feed will be governed primarily by the speed at which the belt travels, and this speed 5 may be regulated in any desired manner, one convenient method being that illustrated, by means of a rheostat control 75 for governing the speed of the motor; other types of speed changing mechanism may, however, be employed to suit 10 conditions of operation. Still another method of controlling the rate of feed could be introduced by simply varying the load represented by the weights 33, thereby disturbing the scale balance and producing a corresponding influence on the 15 control device 70 for regulating the feeding operation.

Thus a weighing feeder is provided in which the material may be fed from the hopper and delivered by the conveyor at either a uniform rate, 20 or at a controlled variable rate as conditions may require. The points of merit of the unique control feature as involved in the operation of the control element 70, and its advantages as applied to a material feeding operation, are quite 25 pronounced. The manner of using this control element in the apparatus which I have described, by attaching it to the conveyor structure which is in turn supported by the scale mechanism (so 30 that the control device is itself a part of the balancing load on the scales), obviously offers not the slightest interference with the normal operation of the scales, and the scale mechanism is not required to perform any other mechanical function (for carrying out the control function) which 35 would in any way interfere with the sensitivity or accuracy of the scale function,—an objection which does in fact apply to some other types of weighing feeders, as for example, where the movement of the scales mechanism is required 40 to mechanically operate a control gate or other mechanism for regulating the amount of material supplied to the conveying or delivery mechanism.

Accordingly, it will be noted that the present 45 improved construction is such as to relieve the scales mechanism entirely of any particular stresses other than those due to the exercise of the normal scales function,—the control element being fully released and free to move after each 50 operating impulse, and the flexible drive shaft arrangement for the conveyor permitting considerable vertical movement of the conveyor without offering any interference with the proper 55 performance of the scale mechanism or with the proper operation of the control function of the wedge member 10. Again, the control action is not only positive but gradual, which gives a continuous and uniform feed action without any sudden starting or stopping of the flow of material 60 from the feeder.

One special advantage of equipment provided with controlled feeding means of this type is the 65 fact that it is particularly well adapted for automatic proportional control, as where the purpose for which the material is being handled requires the amount of material delivered by the feeder to be automatically controlled in proportion to some other mechanical function in accordance with which it is desired to govern the delivery 70 operation of the feeding mechanism. For example, where the apparatus is used to treat water with a given amount of chemical material, the feeding rate of the material may be so controlled that the amount of material delivered by the feeding 75

operation will always be directly proportional to the flow of water being treated.

The provision of the auxiliary troughs or chutes, 17, 18, has the advantage of facilitating 5 the movement and proper placement of the material upon the conveyor belt, without any perceptible lag, from the time it is withdrawn from the hopper until it is deposited upon the belt. The arrangement of the chutes is designed to direct 10 the material to a definite section of the belt, at its rear or receiving end, a baffle member (such as an upright plate 17) being preferably located at this end of the conveyor in position for effectively aiding the proper distribution of the material 15 across this portion of the conveyor. The arrangement herein shown for the chutes provides for their participation in the movement of the feeding tray 12 (as a part of the feeding mechanism), although it will be understood that for 20 materially greater distances between said tray and the top of the conveyor belt, such movement of the chutes may not be necessary, since their angle or pitch might then be such as to require no vibrating action of the chutes in order 25 to discharge the material properly to the conveyor.

It will also be readily understood that the utility 30 of the present improvements is not confined to the feeding of any particular character of materials, such as dry materials in the form of construction herein illustrated; for the nature of the present invention is such as to adapt its operation with equal facility to the feeding of liquid materials, the only modification necessary being 35 with reference to the specific character of the feeding device and the conveyor for the handling of liquid instead of dry or granular material, as for example a construction on the order of that shown in my copending application above referred to.

It will thus be apparent that I have devised a practical and comparatively simple, but efficient and highly accurate form of apparatus for the purposes of feeding weighed quantities of materials, 45 at either a uniform rate or at an effectually controlled variable rate, according to the requirements of the particular installation; and while I have herein shown one practical form of construction for illustrative purposes, it is obvious 50 that the same is susceptible of wide variation or modifications, while still coming within the scope and principle of operation comprising the essential features of my invention. I therefore desire 55 to be understood as reserving the right to all such changes or modifications which may fairly be deemed to fall within the scope of the appended claims.

What I claim is:

60 1. A weighing feeder construction comprising, in combination with a material-supply container, material-feeding mechanism for feeding material from said container, a scales mechanism, a conveyor supported on said scales mechanism and operating to deliver the material as fed thereto by said feeding mechanism, an actuating means and a control member actuated by fluctuations in said scales mechanism for effecting such regulation of the operation of said feeding mechanism as will 65 maintain the scales in balanced condition, said control member being mounted for intermittent engagement with said actuating means and feeding mechanism while free to move between successive driving impulses for allowing said control 70 member entirely idle and independent adjusting

movement in response to fluctuations of said scales mechanism.

2. A weighing feeder construction comprising, in combination with a material-supply container, material-feeding mechanism for feeding material 5 from said container, a scales mechanism, a conveyor supported on said scales mechanism and operating to deliver the material as fed thereto by said feeding mechanism, and driving means for actuating both said conveyor and said feeding mechanism and including a suitable drive connection to the conveyor and also a control element responsive to fluctuations in said scales mechanism for effecting such regulation of the operation of said feeding mechanism as to maintain the scales in balanced condition, said control element mounted for intermittent engagement with said driving means and feeding mechanism while free to move between successive driving impulses for allowing said control element entirely 10 15 idle and independent adjusting movement in response to fluctuations of said scales mechanism.

3. A weighing feeder construction comprising, in combination with a material-supply container, material-feeding mechanism for feeding material 20 from said container, a scales mechanism, a conveyor supported on said scales mechanism and operating to deliver the material as fed thereto by said feeding mechanism, actuating means for said feeding mechanism, and a control member 25 directly actuated by fluctuations in said scales mechanism for interposing said member as a variable drive connection between said actuating means and said material-feeding mechanism.

4. A weighing feeder construction comprising, 30 in combination, a material-supply container, a conveyor operatively arranged beneath said container for delivering the material as discharged from the container, scales mechanism supporting said conveyor, a reciprocating feed tray for feeding the material from said container on to said conveyor, and a pair of chutes arranged in co-operative relation with their discharge ends spaced a predetermined distance apart for directing the material as discharged from said tray 35 uniformly upon a given section of said conveyor.

5. A weighing feeder construction comprising, in combination, a material-supply container, a conveyor operatively arranged beneath said container for delivering the material as discharged 40 from the container, scales mechanism supporting said conveyor, a reciprocating feed tray for feeding the material from said container onto said conveyor, and a pair of oppositely inclined chutes having their lower discharge ends spaced a pre-determined distance apart for directing the material as discharged from said tray 45 uniformly upon a given section of said conveyor.

6. Control mechanism comprising, in combination with a material supply container, a scales mechanism, a conveyor supported on said scales mechanism in position for receiving material as discharged from the container, means for feeding material from the container onto said conveyor and including a driven member having an abutment element, an actuating means provided with a reciprocating abutment element in spaced relation to said first element, and a control element responsive to fluctuations of said scales mechanism and located between said abutment elements for constituting a variable drive abutment between said actuating means and said driven member.
